(57) **CLAIM**

The ornamental design for an electrode assembly for transdermal and transcranial stimulation, substantially as shown and described.

DESCRIPTION

FIG. 1 is a front three-dimensional view of an electrode assembly for transdermal and transcranial stimulation.

FIG. 2 is a front view thereof.

FIG. 3 is a bottom view thereof.

FIG. 4 is a top view thereof.

FIG. 5 is a back view thereof.

FIG. 6 is a right view thereof.

FIG. 7 is a left view thereof.

FIG. 8 is an alternative front view of an electrode assembly for transdermal and transcranial stimulation shown in FIG. 9, worn on a subject's head.

FIG. 9 is a front three-dimensional view of an electrode assembly for transdermal and transcranial stimulation.

FIG. 10 is a front view thereof.

FIG. 11 is a bottom view thereof.

FIG. 12 is a top view thereof.

FIG. 13 is a back view thereof.

FIG. 14 is a right view thereof; and,

FIG. 15 is a left view thereof.

The broken lines showing the remainder of the electrode assembly for transdermal and transcranial stimulation in FIGS. 5, 8 and 13 are directed to environment. The broken lines with the claimed design in FIGS. 5 and 13 that depict circular, overall and square shapes are represent portions of the electrode assembly for transdermal and transcranial stimulation that form no part of the claimed design. None of the broken lines form a part of the claimed design.
